UNITED STATES PATENT OFFICE.

GEORGE A. HIGHFIELD, OF SCRANTON, PENNSYLVANIA.

CAR-COUPING.

SPECIFICATION forming part of Letters Patent No. 431,659, dated July 8, 1890.

Application filed April 16, 1890. Serial No. 348,223. (No model.)

To all whom it may concern:

Be it known that I, GEORGE A. HIGHFIELD, of Scranton, in the county of Lackawanna and State of Pennsylvania, have invented certain new and useful Improvements in Car-Couplings; and I do hereby declare the following to be a full, clear, and exact description of the same, reference being had to the accompanying drawings, forming a part of this specification, and to the letters of reference marked thereon.

My invention has for its object to improve the construction of the car-coupling shown and described in Letters Patent No. 328,584, granted me October 20, 1885, as assignee of E. T. Hall. The objection to the patented device was that as two differently-constructed draw-heads were employed it was necessary to have the cars in a certain relative position, with opposite ends presented to each other, in order to have them couple. By my invention, however, the draw-heads and engaging-hooks are constructed alike, so that they will automatically engage when brought together, as I will now proceed to describe, and point out particularly in the claims at the close of this specification.

In the drawings, Figure 1 represents a perspective view showing the application of my invention to a car. Fig. 2 is a side elevation of two couplings engaged; Fig. 3, a longitudinal sectional view taken on the line $x x$ of Fig. 1.

Similar letters of reference in the several figures indicate the same parts.

A A represent bumpers applied to the end of the draw-bars A' A', and provided with sockets and pins, as in ordinary draw-bars, for the reception of a link-coupling, if from any cause it should become necessary or desirable to employ the same. The buffers are somewhat lower than the bodies of the draw-bars, so as to leave a space above them for the coupling-hooks secured to the upper sides of the draw-bars.

Situated above and resting upon each of the buffers A is a coupling-hook B B, constructed and applied in the following manner: The draw-bars A', provided near their forward ends with a shoulder a, pass under or through the end timbers or sill of the car and are supported to slide thereon in any suitable manner. The coupling-hooks or

draw-heads B B are each pivotally connected on a horizontal plane to the ends of a rod b, 55 passing through the shoulder a on the draw-bar A', said rod b being extended rearwardly through the plates C C', the latter provided with bearings riding in slots in the side pieces C². Between the plates C C' is arranged a 60 spring C³, preferably embracing the rod b, to which latter is also secured a nut b' or a like adjustable collar at a point in rear of the plate C'. As thus constructed and applied, the spring C³ serves not only to hold the head 65 of the bolt b and its coupling-hook or draw-head against the shoulder a of the draw-bar A' and in position for coupling, but it also operates to receive the thrust of the draw-bars and the pull of the coupling-hooks or 70 draw-head, as in either case one of the plates C C', being supported by its lugs at the extremity of the slots in the side pieces C², will resist the movement of the spring in either direction.

The coupling-hooks or draw-heads B B' are each formed with two rearwardly-projecting and curved engaging-points d d' and correspondingly-curved throats d' d', forming an arrow-head, as shown, so that when two of 8c these draw-heads come together the one that happens to be the higher will ride up over the opposite point until both points pass each other and enter the throat d' of the opposite draw-head, and they will then be held securely 85 in engagement. By pivoting the draw-heads, as described, and uniting them by the curved hooks I am enabled to securely and readily couple and hold together cars of different heights.

For the purpose of uncoupling the draw-heads or holding one of them elevated, in order to have it uppermost when coupled, I employ a shaft F, secured in suitable bearings to the car-body and secured to the draw-head 95 by means of a chain f, so that as the shaft is rotated the head may be raised or lowered and held in adjusted position by means of a plate F², having notches in it, with which an arm F' on the end of the shaft is adapted to 100 engage. The shaft is capable of a slight end-wise movement to permit of its being secured to the plates.

The advantages of this device over the patented one will be at once apparent, cars of 105 different heights being permitted to be cou-

pled, the coupling being effected automatically, and that irrespective of the end presented, while, if desired, the heads can be secured up, and the ordinary link-and-pin coupling employed.

5 I claim—

1. In a car-coupling, the combination, with the draw-bars provided with the buffers having the recesses in their ends and vertical shoulders in rear thereof, of the rods passing through the draw-bars and extended beyond the shoulders thereon and upon the buffers, springs applied to said rods to hold them retracted, and the vertically-movable interlocking coupling-hooks secured to said rods and having the engaging-shoulders on their upper and lower sides, substantially as described.
- 10 2. In a car-coupling, the combination, with the draw-bars provided with the buffers having the recesses in their ends and vertical shoulders in rear thereof, of the rods passing through the draw-bars and extended beyond the shoulders thereon and above the buffers, springs applied to said rods to hold them retracted, and the vertically-movable interlocking coupling-hooks secured to said rods and having the engaging-shoulders on their upper and lower sides and means for raising and lowering them, substantially as described.

20 25 GEO. A. HIGHFIELD.
